Justus Parce & Nathan Parce, junior of Chenango Co. N.Y.
Letters Patent

The Schedule referred to in these Letters Patent and making part of the same containing a description in the words of the said Justus Parce and Nathan Parce junior of their improvement in the process of manufacturing Pearl Ashes.

To all to whom these presents shall come. Be it known that we Justus Parce and Nathan Parce, junior of the town of Lincklaen, in the County of Chenango and State of New York, have invented a new and useful improvement in the process of manufacturing Pearl Ashes, and that the following is, a full and exact description of the said improvement, as invented by us. The improvement claimed in the foregoing, will consist in the saving of labor in converting Lye or Black Salts into Pearl Ashes. The improved process is as follows. Extract Lye from the ashes in the usual manner, &c. &c. Let Black Salts be dissolved into Lye. Prepare a tub or Kettle with a false bottom, perforated, so that the lye can pass through. Cover the bottom with a linen cloth, on which spread a layer of common clean sand, about four inches deep, then spread another fine cloth, and upon that, another layer of sand, of about four inches, or deeper. Let the lye be strained through the sand and cloth, and then boiled down to salts. The salts, are then to be buried and buried, in the usual manner, until they become Pearl Ashes. The effect of straining the lye through the sand is to free it from impurity and purify it, so that it can be immediately boiled down, and at once put into the common and converted into Pearl Ashes. Saving the labor of the usual process, to which Lye or Black Salts, must be subjected by the present method of manufacturing. A great quantity of Pearl Ashes is produced in consequence of this, according the necessity of subjecting the lye or Black Salts, to the process of dissolving, dissolving, settling and boiling into white salts, as at present practiced. The only part of the process, a
